UNITED STATES PATENT OFFICE

122,696

DESIGN FOR A WINDOW VENTILATOR OR THE LIKE

Jacob Schwartz, Chicago, Ill.

Application June 17, 1940, Serial No. 93,057

Term of patent 7 years

To all whom it may concern:

Be it known that I, Jacob Schwartz, a citizen of the United States, residing at Chicago, in the county of Cook and State of Illinois, have invented a new, original, and ornamental Design for a Window Ventilator or the like, of which the following is a specification, reference being had to the accompanying drawing, forming part thereof, and in which:

Fig. 1 is a view in perspective looking down-

wardly and toward one corner of my window ventilator or the like showing my new design.

Fig. 2 is a similar view looking from an opposite side.

Fig. 3 is a transverse vertical sectional view taken substantially through the middle portion.

I claim:

The ornamental design for a window ventilator or the like, as shown.

JACOB SCHWARTZ.
